UNITED STATES PATENT OFFICE.

SAMUEL D. CUSHING, OF WESTMINSTER, LONDON, ENGLAND, ASSIGNOR TO JOHN B. SEMPLE, OF SEWICKLEY, PENNSYLVANIA.

PROJECTILE.

1,159,653.

Specification of Letters Patent.

Patented Nov. 9, 1915.

Application filed February 18, 1915. Serial No. 9,407.

To all whom it may concern:

Be it known that I, SAMUEL D. CUSHING, residing at Westminster, in the county of London, England, a citizen of the United States, have invented or discovered certain new and useful Improvements in Projectiles, of which improvements the following is a specification.

My invention relates to improvements in projectiles, and, more particularly, it has to do with the ignition of the tracer material with which projectiles may be equipped.

In order to ignite the tracer material, it has been customary to utilize the motion of the projectile or the pressure of the propelling charge gases to operate a percussion primer, or to rely upon the flash of discharge of the propelling charge either by its unimpeded contact with the tracer material or a more readily ignitable composition at the base thereof, or by such contact attained through an aperture formed in a protective plate or shield by the pressure or heat of the propelling charge gases.

The chief object of the present invention is to provide a reliable and effective projectile tracer adapted to be rendered operative without relying upon percussive action or exposing the combustible material to the flash of discharge or the direct pressure of the propelling charge gases. It will be understood that, with a tracer having such characteristics, the density and composition of the tracer material can be chosen to suit requirements, without having to take into consideration the effect of the pressure or flame of the propelling charge gases upon it.

According to the present invention the heat of the propelling charge gases is utilized indirectly to effect the ignition of the tracer material or a quantity of readily ignitable material serving to ignite the tracer material; that is to say, the gases are not permitted to come into contact with the tracer material or the more readily ignitable material adjacent thereto, which is protected from the said gases by a metallic screen or screen of other substance serving as a heat conductor. With this object, the tracer material may be separated or screened from the propelling charge by a wall of sufficient strength to resist being fractured or de-

stroyed by the heat or pressure, or the heat and pressure, of the propelling charge gases but sufficiently heat conductive to enable the heat of the gases to rapidly penetrate the wall and produce an effect which directly or indirectly causes ignition of the tracer material.

In order that the invention may be clearly understood and readily carried into effect, I will now describe the same more fully with reference to the accompanying drawings which illustrate various constructional embodiments of the invention.

Figure 1 is a longitudinal section of a projectile provided with one of my improved tracers. Figs. 2 to 10^a illustrate various constructional modifications of the tracer. Fig. 11 illustrates in longitudinal section a projectile having a tracer provided with one constructional form of the means I employ to prevent the wadding or spacing disk in the cartridge case from preventing or delaying the ignition of the tracer. Fig. 11^a is a detached view of the tracer of Fig. 11 and in a position at right angles to that of Fig. 11.

In all the figures like reference letters indicate similar parts.

A is the projectile; B is the tracer body, and B' the cell or chamber therein containing the tracer material or composition; C is the plug or cap closing the mouth of the cell or chamber, and C' is a recess or pocket in the plug or cap.

Referring first more particularly to Fig. 1, it is seen that the recess or pocket C' which may be filled with ignitable material (and which may be filled with material more readily ignitable than the body of tracer material with which it is in communication to impart ignition), is formed by removing part of the plug C, leaving a wall c integral with the main portion. The wall c is sufficiently strong to resist being fractured or destroyed by the heat or pressure, or the combined heat and pressure, of the propelling charge gases which make contact with it when the gun is fired, but is sufficiently thin and heat conductive to enable the heat of the gases to rapidly penetrate and thereby raise the temperature of the material in the recess or pocket to its ignition point. The specific material of which this wall c is formed may vary. Copper may be used,

or brass, or other metal, or even non-metallic material. It is necessary, of course, that the wall withstand the impact or rush of gases generated on the firing of the projectile from a gun. Accordingly, given such gas pressure of determinable intensity and given any specific material, and given a certain size for the orifice to be covered, there will be for each material a certain admissible minimum thickness. Each material has its own heat conductivity, and the question in any given case is whether the material selected when made of the minimum thickness permissible will in view of its conductivity afford passage of heat with sufficient rapidity and in sufficient quantity to effect ignition. As I have said, copper and its alloys are serviceable. The burning of the material in pocket C' causes the ignition of the tracer material in the cell or chamber B'. It will be understood that, as soon as the projectile leaves the gun, the plug C will be removed, to leave the tracer chamber unobstructed. This will ordinarily be accomplished thus: When the projectile leaves the gun the pressure of the propelling charge gases on the plug is relieved, the internal pressure due to the burning of tracer material in the cell or chamber of the tracer will blow away the plug C and enable the flame or smoke of the tracer material to pass out at the mouth of the tracer chamber.

In the constructional form of tracer shown in Fig. 2, the recess or pocket C' is formed by boring a hole through the plug C and providing a cover plate c° to serve as the above mentioned thin wall, the said plate being kept in position in any convenient manner, as for instance by slightly beveling the edge of the plate and forcing the adjacent metal of the plug to overlap the bevelled edge. Thus secured, the plate will resist being forced inward but will be blown off rearwardly with comparative ease when the projectile and tracer leave the muzzle of the gun and are relieved of the propelling charge gas pressure. The plate need not be formed from the same metal as the plug but may, if desired, consist of metal or material more suited to the thermal function required of it. A perforated disk or washer c° may be provided to partially cover the forward face of the material (ordinarily more readily ignitable material) in pocket C', but it will be understood that if this material is of such composition that it is not likely to become displaced or loose, this washer may be omitted. The material of which the washer is made is unimportant; it may be of combustible or of readily fusible or of heat resisting material. In this construction the plug is held in position in the mouth of the tracer chamber by screw threads F, and when the projectile and tracer leave the muzzle of the gun the pres-

sure of the gases in the tracer chamber forces the washer c° and the plate c° out of the hole in the plug, leaving a clear passage for the smoke and flame of the burning tracer material.

In the modification shown in Fig. 3, the readily ignitable material in the recess of pocket C' is contained in a metal cup C°, which may be held in position in any suitable way; for example, in the same way as the cover plate c° in Fig. 2, is held.

The modification shown in Fig. 4 is similar to that shown in Fig. 1, excepting that a washer c° is provided as in Fig. 2, and that the wall c is so shaped as to provide an extended surface for contact with the propelling charge gases.

In the modification shown in Fig. 5, the closure for the mouth of the cell or chamber B' is in the form of a cap, and the pocket C' is in the form of a hollow protuberance, presenting an extended surface for contact to the propelling charge gases.

Although I have described several embodiments of the invention in which a recess or pocket in the plug or cap at the mouth of the tracer chamber contains readily ignitable material, the recess or pocket need not necessarily contain material dependent for its action upon the attainment of an ignition temperature. For example, the material may be such that the penetration of heat to it through the above mentioned heat conductive wall will cause it to become operative without igniting; in the construction shown in Fig. 6, for instance, the material is a liquid inclosed in a glass or other case D fitting into the recess or pocket, the nature of the liquid and its relation to the tracer material or to supplementary material adjacent thereto being such that, when the penetration of heat through the wall c to the case D containing the liquid causes the liquid to escape by rupturing the case or otherwise, the chemical action of the liberated liquid on the tracer material or on adjacent supplementary material will bring about the desired ignition. Such ignition by chemical action is, for example, attained when sulfuric acid is allowed to react upon a mixture of sugar and chlorate of potash.

In all forms of the tracer it will be understood that the thickness of the wall screening the tracer material or adjacent supplementary material from direct contact with the propelling charge gases is dependent upon the conductivity of the material of which it is composed and the rapidity with which it is desired to raise the temperature of the said tracer material or tracer-igniting material.

The plug or cap itself may be held in or upon the mouth of the tracer chamber or cell in any convenient manner, depending upon

the degree of security desired. For example, merely by friction, as shown in Figs. 3, 4, 5 and 11; by a filling of lead or cement as shown at E in Fig. 1; by a set screw G, as shown in Fig. 9, capable of being sheared when the gun is fired; or by screw threads as already described in connection with Fig. 2. Alternatively, as shown in Fig. 8, the plug may be kept in position by a resilient 10 split ring H capable of receding into a recess H' in the wall of the tracer chamber when the plug is being thrust into position and of ultimately springing forward into a circumferential groove on the plug. When 15 the plug is being blown out rearwardly from the mouth of the chamber, this locking ring is either sheared or is forced back into the recess H'. A spring K', as shown, may if desired be provided to hold the plug firmly 20 in position and assist in its expulsion from the mouth of the chamber at the proper time.

In the constructional arrangement shown in Fig. 7, the plug is kept in position in the mouth of the cell or chamber B' by a disk J, 25 the flared edge of which is adapted to spring into locking engagement with a circumferential notch J' in the wall of the tracer chamber at the mouth thereof. A spring K may be provided to keep the plug firmly in contact with the locking disk. In this figure the recess or pocket C' in the plug C is shown open at the rear, and the central part of the locking disk J serves as the inclosing conductive wall; whereas, in the modification shown in Fig. 7^a, the wall at the rear of the recess or pocket is integral with the plug, and the locking disk J has a central perforation to enable the propelling charge gases to make direct contact with the wall. In the 30 construction shown in Fig. 7 it will be understood that, when the gun is fired, the gas pressure will cause the locking disk and the plug to be pressed some distance into the mouth of the tracer chamber against the opposition of the spring, thereby causing the locking disk to become disengaged from the notch J' and its flared edge to become contracted, so that when the projectile leaves the gun the plug will be free to be blown 35 out of the mouth of the chamber, taking the locking disk with it. In Fig. 8 also the plug C will first be driven forward toward the charge of tracer material and subsequently expelled.

It is to be observed that in the constructions shown by Figs. 1 to 6 the propelling charge gases are able to make direct contact with the whole rear surface of the plug, whereas in Fig. 7^a they are able to make direct contact with a part only.

In Fig. 10 a further alternative arrangement is shown; the gases eventually make contact with the whole rear surface of the disk J at the rear of the plug, but in the first instance they are directed through a

nozzle L in a protective disk M so as to impinge on the heat conductive wall constituted by the central part of the disk J, and thus the heating is intensified and localized.

In Fig. 10^a I show further refinements of 70 the structure of Fig. 10, which present conditions of service suggest. As in Fig. 10, the hole in disk M affords a blow-pipe effect, concentrating the inrush of highly heated gases upon the center of copper plate J. 75 This copper disk J, in turn, rests against plug C, with an interposed centrally perforated heat insulating disk R (which may be of paper) arranged between. The copper plate J is heavy enough to stand the pressure of the impinging stream of gases. The recess C' in the plug C is filled preferably with such a readily ignitable material as the following compound: fulminate of mercury, 10%; chlorate of potassium, 20%; and black 80 powder, 70%. As indicated in Fig. 10^a, a space is preferably left between the pellet of 85 readily ignitable material in pocket C' and the rear face of the body of tracer material.

It may happen that pieces of the wadding 90 or spacing disk sometimes inserted in the cartridge case between the projectile and the propelling charge may be crushed or otherwise forced against the base of the projectile when the gun is fired, thereby preventing free access of the propelling charge gases to the above described heat conductive wall at the mouth of the tracer chamber, and thus as it were insulating the wall against the desired heating effect. In order to prevent 95 such an occurrence, the tracer chamber may be provided at its base with a projecting skeleton framework or other means, adapted to shield the space immediately to the rear of the mouth of the tracer chamber so as to prevent this space from becoming choked and to divert any pieces of the wadding or spacing disk away therefrom. One constructional arrangement for this purpose is shown in Figs. 11 and 11^a, where the rear end or base of the tracer body B is shown provided with a rearwardly directed skeleton framework N. It will be understood that in the event of the wadding or 100 spacing disk O between the projectile A and the propelling charge P becoming crushed or otherwise forced toward the base of the tracer, the framework N will serve to shield the thin wall e, and thereby insure that the propelling charge gases shall have free access to the thin wall. The said framework may be integral with the tracer stock or be 105 screwed or otherwise secured thereto.

I claim as my invention:

1. A projectile provided with a tracer chamber and means for protecting a body of tracer material within said chamber from the contact of gases generated on firing the projectile from a gun, such means constituting a heat-conducting medium between 115 120 125 130

such gases of firing and such body of tracer material and affording heat transmission in ignition-producing quantity.

2. A projectile provided with a tracer chamber opening through its posterior face and a screen arranged in the mouth of said chamber; such screen being impenetrable to the gases generated on the firing of the projectile from a gun but being heat conductive and affording heat transmission from such gases of firing to a body of tracer material within said chamber in ignition producing quantity.

3. A projectile provided with a tracer chamber and a closure for said chamber, said closure being heat conducting and affording transmission of heat in ignition-producing quantity from the gases generated on the firing of the projectile from a gun to a body of tracer material within said chamber, said closure being furthermore removable during the flight of the projectile from its position by gas pressure consequent upon ignition of a body of tracer material within said chamber.

4. The combination of a projectile having a tracer chamber opening through its posterior face, a heat-conducting closure for said chamber affording ignition to a body of tracer material within said chamber by heat communicated from the gases of firing, and a fender for said heat-conducting ignition-affording closure.

5. The combination of a projectile provided with an outwardly opening tracer chamber, a closure for said chamber, a body

of tracer material within said chamber, a body of ignitable material arranged within said chamber, adjacent said closure, and intermediate between said closure and said body of tracer material, said closure being formed of heat-conducting material and affording, on the firing of the projectile from a gun, the transmission of heat in ignition-producing quantity from the gases generated on firing to the said body of ignitable material.

6. A projectile provided with a tracer chamber, a closure for said chamber formed of heat-conducting material and affording when the projectile is fired from a gun the transmission of heat in ignition-producing quantity from the gases of firing to a body of tracer material within said chamber, and a perforate disk arranged in the mouth of said chamber external of and at an interval from said closure.

7. The combination of a projectile provided with a tracer chamber and a closure arranged in the mouth of said chamber, said closure and the wall of said tracer chamber provided with interlocking portions preventing displacement under normal conditions, such interlocking being however destructible by forces released on the firing of the projectile from a gun.

In testimony whereof I have hereunto set my hand.

SAMUEL D. CUSHING.
